GARMENT

Montie M. Brohard, Jr., Norwood, Ohio

Application October 8, 1947, Serial No. 778,550

4 Claims. (Cl. 2—116)

1

This invention relates to a garment, and concerns particularly a shirt or jacket type of garment embodying certain novel features of construction.

One of the objects of the invention is to provide a garment of unusual but attractive appearance, departing from the conventional type of shirt or jacket.

Another object is to provide a revolutionary style of collar construction for a shirt or jacket.

A further object is to provide in a garment a collar of novel construction having no conventional collar points to become disarranged, out of shape, or otherwise disheveled, the collar being at all times smoothly arranged on the body of the wearer.

Another object of the invention is to provide a garment construction having the foregoing characteristics without sacrificing any of the comfort to the wearer.

These and other objects and advantages are attained by the means described herein and illustrated upon the accompanying drawing, in which:

Fig. 1 is front view of the garment as it appears upon the person of the wearer.

Fig. 2 is a rear view of the same.

Fig. 3 is a fragmental front view of the garment, showing the collar laid back to a V-neck position, part of the garment being broken away to show its construction.

Fig. 4 is a fragmental front view of the garment as worn with a four-in-hand tie.

Fig. 5 is a view of the collar piece, partly folded and partly flattened, which forms part of the invention.

Fig. 6 is a cross sectional view taken on line 6—6 of Fig. 5.

Fig. 7 is a cross-sectional view taken on line 7—7 of Fig. 5.

The garment of the present invention is an innovation in shirt or jacket design, in that it departs from the conventional type of collar construction usually employed in garment manufacture. Because its novel construction, the garment presents an unusually attractive appearance, whether worn with the collar closed at the neck, with or without a tie, as shown in Figs. 1 and 4, or open at the neck, as in Fig. 3. The comfort of the wearer has not been sacrificed, but rather, if anything, enhanced, since he need no longer be concerned with unruly collar points which often presented a problem in the conventional type of garment. As a study of the drawings will show, the usual collar points are non-existing in the garment of the present inven-

2

tion; thus eliminating the problem of controlling collar points to maintain them in neat condition, much to the relief of the sartorially fastidious.

The garment may be made with any of the standard shirting or jacket materials, and, if desired, parts of the garment may be made of one material or color, and other parts of a different color or material. The garment may be provided with long or short sleeves, the former being shown upon the drawings, it being understood that the style of the garment is not to be limited to the type exemplified.

The principal parts of the garment comprise the right and left front panels 9 and 10, the back panel 12, the sleeves 13 and 14, the collar 15, and the yoke 16. The back is shown as being in one piece; although it may be made with several panels if desired, and may be gathered at the back and yoke seam 17, as shown in Figs. 2 and 3. The front panels 9 and 10, commonly called fronts, extend vertically from the bottom or tail edge 18 of the garment to the shoulder seams 19 and 20, and transversely from the meeting or closing edges 21 and 22 around to the side seams 23 and 24, where the front panels meet the back 12. The sleeves 13 and 14, of course, are stitched into the armholes of the garment in the usual manner, at the seams indicated at 25 and 26. One or more pockets 28 may be provided, either of the set-in or patch type.

The yoke 16 preferably comprises two or more thicknesses or layers of material, although a single panel may be used. The yoke is set into the shirt in the usual manner, the method of inserting and sewing thereof being a matter of immateriality to the invention.

Except for the construction of the collar 15, the garment shown in the drawings is more or less conventional. Only that stitching which refers to the collar construction is shown upon the drawings, it being understood that suitable stitching or sewing is employed in joining together the component parts of garments at the seams hereinbefore described.

The collar 15 comprises an irregularly shaped piece of material 29, shown partly in folded condition and partly in flattened condition in Fig. 5. The central section 30, which connects the two wing-like members 31 and 32, forms the folded rear collar portion 33 of the completed garment. The wing-like members 31 and 32 overlap the upper portions of the shirt front panels 9 and 10, respectively, as shown in Figs. 1, 3, and 4, 65 extending from the central front collar meeting

point 34 (Fig. 1), to each side seam 23 and 24 beneath the armpits 35, Fig. 3.

A major portion of the outline of the wings 31 and 32 conforms to the outline of the upper portions of the front shirt panels 9 and 10. The upper straight margins 35' and 36 are sewed to the shirt along with the front panels 9 and 10, at the shoulder seams 19 and 20, respectively, by means of stitching 38, while the arcuate margins 39 and 40, form a portion of the armscyes to which the sleeves 13 and 14 are attached, the stitching of which is indicated at 41. The short margins 42 and 43, of the collar piece 29, are joined to the rear shirt panel 12 at the side seams 23 and 24, as shown under the right sleeve at 35 in Fig. 3, the stitching thereof being shown at 44.

The outer margin 45 of the wing connecting member 30, Fig. 5, is in detached relation to the back of the shirt, as shown in Fig. 2. Prior to sewing the collar piece 29 to the body of the shirt, a suitable hem 46, Figs. 5 and 6, may be provided on the collar piece margin 45. The relation of the collar 15 to the shirt, at the back thereof, is substantially the same as that of a conventional shirt or jacket, as will be understood from Fig. 2, the lower margin 45 being in detached relationship, as hereinbefore recited.

The inner margin 48 of the wing connector 30, Figs. 5, 6, and 7, may be attached to the yoke 16 in the conventional manner, as shown at the seam 49 in Figs. 1, 3, and 4, the stitching of which is indicated at 50. The collar is thus folded substantially upon the longitudinal center line 47 of the wing connector 30.

The depending tabs 51 and 52 of the collar piece 29 are suitably secured to the shirt front panels 9 and 10, respectively, in the following manner: The tabs 51 and 52 are turned under (tab 51 being shown in this position in Fig. 5), so that the marginal edges 53 and 54 of said tabs coincide with the meeting or closing edges 21 and 22 of the shirt fronts 9 and 10, the respective edges being stitched together as indicated at 55 in Figs. 1 and 3. The tabs 51 and 52 may be of any desired length, extending for the entire length of the front panels to the bottom or tail edge, if preferred.

The final step in assembling the collar piece 29 is to sew the lower margins 58 and 59 of the wing members 31 and 32 to the shirt front panels 9 and 10, as indicated at 60 and 61, respectively, in Figs. 1, 3, and 4. It will be noted that the stitching 60 and 61 extends from the side seams 23 and 24 to a point 62 remote from the collar meeting point 34. Prior to applying the stitches 60 and 61 which connect the wing members 31 and 32 to the shirt fronts, the wing margins 58 and 59 may be suitably hemmed to provide a finished edge thereto. The detached portions of the collar front between the stitching termini 62 and the collar meeting point 34 permit the wearer of the garment to insert a necktie 63, Fig. 4, through the annular channel so provided, if he chooses. The loop or bight 64 of the tie 63 is indicated by broken lines in Fig. 4.

An alternative construction of the shirt front panels is shown in Fig. 3. In the exemplified form, a major portion of the material of the shirt panels underlying the collar wing members 31 and 32 may be cut away as indicated at 65 in Fig. 3, in order to effect economy in the use of material. In this case, the wing members 31 and 32 serve to complete the front panels, the fin-

ished garment giving no outward indication that the front panels have been cut away.

Any one of several closure means for the garment may be employed, buttons 66 being indicated upon the drawings. Other closure means may include slide fasteners, snaps, and the like.

As herein disclosed, the garment of the present invention is so constructed as to provide advantages never before attained in the art. The unusual collar effect is a radical departure from anything hitherto produced in the sartorial art, being both pleasing in appearance, and comfortable to the wearer. There are no collar points to bend outwardly from the shirt front or otherwise become awry, as in the conventional type of garment. The entire garment, whether buttoned at the neckline or worn open at the neck, as shown in Fig. 3, and whether or not worn with a necktie, scarf, or the like, presents a much desired novel effect never heretofore attained.

It is to be understood, of course, the various structural modifications may be made within the scope of the appended claims, without departing from the spirit of the invention. For instance, the tail portion may be eliminated and a waistband provided instead, the sleeves may be long or short or entirely omitted, and the pocket may be omitted or other pockets added. Furthermore, the width of the collar at the rear (Fig. 2) is not to be necessarily restricted to the width shown, as it is possible to increase this dimension for the purpose of imparting a cape effect across the rear of the garment. In such a case it may be desirable to omit the yoke, and resort to the equally conventional practice of stitching the top of the shirt fronts to the top of the back at the shoulders; and in fact, the garment illustrated by the accompanying patent drawings may be so constructed in accordance with the common practice, if desired.

What is claimed is:

1. A shirt or jacket type of garment comprising front sections and a back section terminating at their upper ends in a neck portion and being provided with armscyes, a foldover type of collar secured to said neck portion and a wing carried by each end of the outer collar fold at the front of the garment and extending in opposite directions across a front section of the garment and terminating adjacent an armscye, the front edges of said wings diverging downwardly and means for securing each wing to a front section of the garment.

2. A shirt or jacket type of garment comprising front sections and a back section terminating at their upper ends in a neck portion and being provided with armscyes, a foldover type of collar secured to said neck portion and a wing carried by each end of the outer collar fold at the front of the garment and extending in opposite directions across a front section of the garment and terminating adjacent an armscye, the front edges of said wings diverging downwardly and means for securing each wing to a front section of the garment and to said armscyes.

3. A shirt or jacket type of garment comprising front sections and a back section terminating at their upper ends in a neck portion and being provided with armscyes, a foldover type of collar secured to said neck portion and a wing carried by each end of the outer collar fold at the front of the garment and extending in opposite directions across a front section of the garment, and terminating adjacent the armscyes, the front edges of said wings diverging downwardly, and

means for securing each wing to a front section of the garment, a portion of said securing means extending along said diverging edge of the wing throughout only a portion of its length to provide an opening through which a tie may be passed.

4. A shirt or jacket type garment comprising front sections and a back, both terminating at their upper ends in a neck portion and the garment being provided at opposite sides with armscyes, a foldover collar comprising an inner and an outer layer for encircling the neck of the wearer with the inner layer secured to said neck portion and the outer layer of said collar at each front end thereof being provided with a relatively wide wing, each wing extending from the center of the garment across a front section and terminating adjacent an armscye and means for securing each wing to the said front section.
